Des. 214,772
Patented July 22, 1969

214,772

COMBINED CUTTER AND TENDERIZER FOR FRANKFURTERS OR THE LIKE

Robert C. Carson, 15809 Loukelton St.,
La Puente, Calif. 91744

Filed Sept. 9, 1968, Ser. No. 13,466

Term of patent 14 years

Int. Cl. D7—05, 99

U.S. Cl. D89—1

FIG. 1.

FIG. 2.

FIG. 3.

FIG. 4.

In the drawing:

FIGURE 1 is a perspective view of a combined cutter and tenderizer for frankfurters or the like, showing my new design;

FIGURE 2 is a plan view thereof;

FIGURE 3 is an elevational view thereof; and

FIGURE 4 is an end view thereof.

I claim:

The ornamental design for a combined cutter and tenderizer for frankfurters or the like, as shown.
